corporation of Massachusetts

Application April 4, 1939, Serial No. 265,908

11 Claims. (Cl. 250—20)

The present invention relates to electric systems, and more particularly to systems for eliminating or rejecting undesired voltages. From a more specific aspect, the invention relates to static eliminators, or limiters, as they are usually called, for radio-receiving systems.

Prior proposals for eliminating, in radio receivers, the peaks produced by external forces, such as static caused by disturbances in the atmosphere, or by motors and other electric machinery in the neighborhood, have been attended with some degree of success, but they have not been entirely effective. Many of these proposals have utilized a diode or similar device to block transmission of the signal through the receiving system when the signal voltages exceed normal values. Prior systems of this kind, however, have been of such nature that only a portion of the undesired signal peaks are thus eliminated.

An object of the present invention is to provide a new and improved system of this character that shall eliminate the whole undesired peaks.

One reason for the failure of prior proposals of this nature has been that the diode or similar device has been so connected into circuit that it could not respond rapidly enough to the undesired peak voltage.

A further object of the invention, therefore, is to provide a new and improved system of the above-described character that shall respond instantly.

Other and further objects will be explained hereinafter, and will be particularly pointed out in the appended claims.

The invention will now be explained in connection with the accompanying drawings, in which Fig. 1 is a diagrammatic view of one type of radio-receiving circuit embodying the invention; Figs. 2 to 4 are explanatory graphs; Fig. 5 is a fragmentary view similar to Fig. 1 of a modification; Fig. 6 is a view similar to Fig. 1 employing two rectifiers for respectively eliminating the positive and negative peaks; and Fig. 7 is a graph corresponding to Fig. 3 for the circuit of Fig. 6.

Referring, first, to Fig. 1, radio signals, received by an antenna 2, are passed through a radio-frequency amplifier 4 and a first detector 6, where they are heterodyned through the medium of a beating oscillator 8. The heterodyned signals, after amplification by an intermediate-frequency amplifier 10, are demodulated by a second detector 12 and amplified by an audio amplifier 14, after which they are evidenced in telephones or a loud speaker 16. The radio re-

ceiver illustrated in Fig. 1 will serve as a setting for a description of the invention, but it will be understood that the invention is not limited to use with any particular type of radio-receiving circuit. The invention is of general application and could be used even in transmitters.

If the signals, when first arriving at the receiving antenna 2, or at some later point, are accompanied by static or other disturbances, these disturbances will be treated by this radio receiver in the same way as the signals themselves, and will be delivered in the telephones or loud speaker 16 in the form of clicks, buzzes, or other distortion.

15 This will be understood from Figs. 2 and 3. The signal may be assumed, when reaching the antenna 2, to have the carrier envelope shown in Fig. 2, including noise-pulse positive and negative peaks 18 and 20. The second detector 12 will rectify the signal, suppressing either the positive or the negative half. The negative half is assumed to be suppressed, according to Fig. 3, but it is still accompanied by the noise peak 18.

20 According to the present invention, the peak 18 is eliminated from the rectified signal by means of a diode valve 22 or similar device, suitably connected into circuit at some suitable point. It is shown connected between the second detector 12 and the audio amplifier 14, but it may be connected elsewhere, as at the output of the intermediate-frequency amplifier 10, or just before the audio stage of the receiver. In Fig. 6, for example, employing two diodes, the limiter is connected at the output of the intermediate-frequency amplifier.

25 The cathode 24 of the diode 22 is shown connected to the output of the second detector 12, through an isolating condenser 26, and its anode 28 to the input of the audio amplifier 14, through an isolating condenser 30. The positive terminal 32 of an adjustable direct-current voltage source, such as a potentiometer 34, is connected, through a resistor 36, to the anode 28, and its negative terminal 38, through a resistor 40, to the cathode 24. The connection of either the positive terminal 32 to the anode 28, or the negative terminal 38 to the cathode 24, or both, may be adjustable; the adjustment is illustrated as effected by a slider 42. The adjustment is such as to render the anode 28 positive with respect to the cathode 24, else the diode 22 will not be conducting. A circuit for direct current is thus established from the positive terminal 32 of the potentiometer 34, through the resistor 36, the anode 28, and the cathode 24 of the diode 22, and the resistor

40, to the slider 42 at the negative terminal 38 of the potentiometer 34. Audio-signal voltages applied to the condenser 26, therefore, will be transmitted through the diode 22 in a direction opposite to the conventionally accepted positive direction of current in the direct-current circuit through the diode 22. The audio voltage appearing at the condenser 30 is thus a function of the variation in the direct current through the resistor 36, resulting from the audio signal through the diode 22, and this produces a voltage drop across the resistor 36. The audio voltage appearing at the condenser 30 becomes superimposed upon the voltage drop across the resistor 36 at the anode 28, and will appear as shown in Fig. 3; or rather, as will hereinafter appear, with the peak 18 eliminated, as in Fig. 4.

Where the limiter is connected just following the second detector, as shown in Fig. 1, and where this second detector is of the type that delivers a pulsating audio voltage that is always positive in potential, it is obviously essential that the diode 22 or other device employed have a positive terminal 28 and a negative terminal 24, and that it be connected into the system with the negative terminal 24 disposed nearer to the antenna 2, and with the positive terminal 28 disposed nearer to the telephones or loud speaker 16. The signals received by the antenna 2 will then be transmitted through the diode or other device 22 in the direction from the negative terminal 24 toward the positive terminal 28. Obviously, therefore, if the positive-terminal anode 28 should, at any time, become negative with respect to the negative-terminal cathode 24, as may take place for currents having too great a positive voltage, the excess voltage can not be transmitted through the diode 22, and will become eliminated from the system before the signal, shown in Fig. 4, reaches the telephones or loud speaker 16.

If, on the other hand, the second detector is of the type that delivers a pulsating audio voltage that is always negative in potential, these connections and also the battery polarity should be reversed. The following discussion will be based upon the circuit diagram shown in Fig. 1 to fix the ideas.

In order to eliminate the peak 18, or other voltages corresponding to the disturbances to be eliminated, therefore, it is merely necessary to adjust the degree to which the anode 28 is positive with respect to the cathode 24, so as to permit transmission of so much of the rectified signal as is indicated below the line 44, and to suppress the peak portion of the signal above the line 44. This may, for example, be effected by suitable choice of the resistors 36 and 40 and suitable adjustment of the slider 42 on the potentiometer 34. The anode 28 will then remain positive with respect to the cathode 24, and the diode 22 will be conducting, so long as the signal voltages remain below the line 44, but the anode 28 becomes immediately negative with respect to the cathode 24, and the diode 22 becomes non-conducting, the moment that the signal voltages rise above the line 44. The diode can not, therefore, transmit the peak 18, or any part of it, because it becomes instantaneously non-conductive as soon as any part of this peak voltage becomes impressed upon it.

By varying the position of the slider 42, the potential applied to the diode 22 can be varied between zero and a maximum corresponding to the positive voltage of the positive terminal 32 of the potentiometer, which may, for example, be in the

neighborhood of 50 volts. The potential of the anode 28 depends upon a number of factors, principally upon the resistances of the resistors 36 and 40, the adjustment of the slider 42, and the average audio level of the signal transmitted through the condenser 26.

As an illustration, let it be assumed that it is desired to eliminate from the signal all voltages greater than one volt, as indicated by the line 44. The resistors 36 and 40 may be so chosen and the slider 42 so adjusted that the potential difference between the anode 28 and the cathode 24 of the diode 22 normally tends to be one volt. Audio-signal voltages less than one volt will then produce variations at the condenser 30 within the one-volt limit below the line 44, and the peaks 18 above the line 44 will be eliminated by the diode 22 completely shutting off the flow of current at all times, as soon as the cathode 24 becomes positive with respect to the anode 28.

By adjusting the potentiometer 34, obviously, line 44 may be raised or lowered in Fig. 3, so as to adjust the portion of the peak 18 to be eliminated and even, if desired, part of the so-called useful wave itself. This latter condition will, of course, produce considerable distortion of the audio wave, but is very useful in certain applications as, for instance, when receiving intermittent code signals that do not require accurate reproduction in wave form.

According to certain prior-art devices, the diode 22 or its equivalent has been so connected into circuit that it was normally non-conducting, so as never to pass any part of the useful signal, but was rendered conducting in response to undesired peak voltages, and this conducting state of the diode was utilized to eliminate the peak. Because diodes and similar devices of this nature are imperfect conductors when the anode 28 is only slightly positive with respect to the cathode 24, however, their response, at such times, is sluggish, and it is not until the anode 28 becomes positive with respect to the cathode 24 to the extent of, usually, two or three volts, that the diode 22 becomes sufficiently well conducting. The lower part of the peak voltage does get through the diode, therefore, before the diode can respond to the peak stimulus to block the remainder of the peak voltage. Peak suppression according to these prior-art devices, however, is relatively ineffective. A feature of the present invention resides, as above indicated, in so connecting the diode 22 or similar device into circuit that it is normally conducting in the direction from the cathode 24 to the anode 28, but becomes non-conducting upon the occurrence of undesired peak voltages. Except upon the occurrence of these peak currents, the diode 22 is at all times conducting in the direction from the cathode 24 to the anode 28, so as always to transmit the useful audio signals of voltages smaller than the voltage indicated by the line 44. This action of the diode 22 is definite and complete, since the diode 22 is essentially a perfect insulator when the cathode 24 is positive with respect to the anode 28. The response to undesired peak voltages is thus rendered immediate and the complete undesired peak voltages become eliminated.

It has been assumed above that the second detector 12 suppresses the negative half of the envelope shown in Fig. 2. If it should suppress the positive half, transmitting the negative half, the negative peak 20 would be eliminated by the same arrangement, with an interchange of the connections of the anode 28 and cathode 24 of

the diode 22, and with the terminal 32 connected to a negative, instead of a positive, voltage.

The anode 28 would still be adjusted to a positive voltage with respect to the cathode 24.

The invention is not, however, confined to limiting action necessary for changes of potential that occur in one direction only. If the limiting device of the present invention were connected at some point in the intermediate-frequency amplifier 10, for example, as illustrated in Fig. 6, where a symmetrical signal envelope would be impressed upon it, the limiting action could be arranged on both the positive and the negative sides. This would be effected with the aid of two limiting valves 51 and 54, the valve 51 for limiting the peaks 58 on one side of the envelope, and the valve 54 having a similar action on the peaks 56 on the other side of the envelope. The anodes and cathodes of the valves 51 and 54 may be interchanged, in which case the battery polarity would be reversed to maintain the anodes positive.

There is a phenomenon, called "contact potential," that requires at least a minimum voltage on the anode 28 of the diode 22 before electrons will travel from the cathode 24 to the anode 28. In such cases, for very small impressed signal voltages, it may become necessary, when the line 44 is moved very low down toward zero voltage, to adjust the slider 42 to a value positive with respect to the terminal 32. This may be accomplished in any desired way, as by connecting the resistor 36 to an intermediate point 46 of the potentiometer 34, as shown in Fig. 5. The slider 42 may then be adjusted to the right of the point 46.

As the static eliminator or limiter of the present invention is shown connected to the audio branch of the second detector 12, the parameters of this limiter should be taken into consideration in the design of the audio circuits and of the second detector 12. This is particularly important in the case of a diode second detector 12 of the type shown, wherein it is desirable to maintain equal loads at the condenser 26 for both direct-current and alternating-current voltages of the carrier envelope. From the practical standpoint, the limiter circuits will impose a fairly large alternating-current load, but zero direct-current load, with the action of the coupling condenser 26, and this effect may, in some cases, introduce second-detector distortion at high levels of carrier modulation. The means for overcoming this are well known. Since it is necessary only to equalize alternating-current and direct-current loads, the difficulty may be overcome by connecting the condenser 26 to an intermediate point 48 of a resistor 50 connected to the cathode 52 of the second detector 12, instead of directly to this cathode. By thus connecting to the intermediate point 48, compensation will be made for the impedance of the resistors 36 and 40 of the limiter.

Further modifications will occur to persons skilled in the art and all such are considered to be within the scope and spirit of the invention, as defined in the appended claims.

What is claimed is:

1. In combination with an electric system from which it is desired to eliminate voltages having a value higher than a predetermined voltage, a tube having a cathode and an anode that is normally positive with respect to the cathode, means for transmitting negative half-wave currents in the system through the tube in the direction

from the anode towards the cathode, means for rendering the anode negative with respect to the cathode upon the occurrence in the system of a voltage higher than the predetermined voltage, and means for rendering the rendering means independent of the magnitude of the predetermined voltage.

2. A static eliminator having, in combination with a receiving system provided with a signal-receiving portion and a signal-delivering portion, a tube having a cathode and an anode and connected with the receiving system so that signals received by the signal-receiving portion shall be transmitted through the tube in the direction from the cathode towards the anode for a positive half wave and from the anode towards the cathode for a negative half wave to the signal-delivering portion, means for maintaining the anode positive with respect to the cathode to a degree less than the voltage corresponding to the static to be eliminated from the signals, and means for maintaining the said degree independent of the average magnitudes of the signals.

3. A static eliminator having, in combination with a receiving system, a condenser connected with the receiving system, a tube having a cathode and an anode and connected with the condenser so that signals received by the receiving system shall be transmitted through the condenser and the tube in the direction from the cathode towards the anode for a positive half wave and from the anode towards the cathode for a negative half wave, a potentiometer, means for connecting the positive terminal of the potentiometer to the anode, means for connecting the negative terminal of the potentiometer to the cathode, and means for adjusting the potentiometer to maintain the anode positive with respect to the cathode to a degree less than the voltage corresponding to the static to be eliminated from the signals.

4. A static eliminator having, in combination with a receiving system, a condenser connected with the receiving system, a tube having a cathode and an anode and connected with the condenser so that signals received by the receiving system shall be transmitted through the condenser and the tube in the direction from the cathode towards the anode for a positive half wave and from the anode towards the cathode for a negative half wave, a potentiometer, two resistors, means for connecting the positive terminal of the potentiometer through one of the resistors to the anode, means for connecting the negative terminal of the potentiometer through the other resistor to the cathode, and means for adjusting the potentiometer to maintain the anode positive with respect to the cathode to a degree less than the voltage corresponding to the static to be eliminated from the signals.

5. In combination with an electric system from which it is desired to eliminate voltages having greater than an undesired magnitude, two means each having a negative terminal and a positive terminal, means for impressing upon the said respective two means voltages of substantially the said magnitude but of opposite polarity, means for transmitting the said voltages through one of the said two first-named means in the direction from the negative terminal toward the positive terminal for a positive half-wave and from the positive terminal toward the negative terminal for a negative half-wave and through the other of the said two first-named means in

the direction from the negative terminal toward the positive terminal for a positive half-wave and from the positive terminal toward the negative terminal for a negative half-wave, and means for rendering the positive terminals negative with respect to the negative terminals upon the occurrence in the system of a voltage corresponding to the undesired voltage.

6. A static eliminator having, in combination with a receiving system having an intermediate-frequency amplifier and a second detector, two means disposed between the intermediate-frequency amplifier and the second detector and each having a negative terminal and a positive terminal, means for transmitting signals received by the receiving system through the intermediate-frequency amplifier, means for thereafter impressing the positive half-waves of the signals upon one of the first-named means and the negative half-waves of the signals upon the other of the first-named means, means for transmitting the signals through one of the first-named means in the direction from the negative terminal toward the positive terminal for a positive half-wave and from the positive terminal toward the negative terminal for a negative half-wave and through the other of the said two first-named means in the direction from the negative terminal toward the positive terminal for a positive half-wave and from the positive terminal toward the negative terminal for a negative half-wave, and means for maintaining the positive terminals positive with respect to the negative terminals to a degree less than the voltage corresponding to the undesired voltage.

7. In combination with an electric system from which it is desired to eliminate voltages having greater than an undesired magnitude, two means each having a negative terminal and a positive terminal, means for impressing upon the said respective two means voltages of substantially the said magnitude but of opposite polarity, means for transmitting the said voltages through one of the said two first-named means in the direction from the negative terminal toward the positive terminal for a positive half-wave and from the positive terminal toward the negative terminal for a negative half-wave and through the other of the said two first-named means in the direction from the negative terminal toward the positive terminal for a positive half-wave and from the positive terminal toward the negative terminal for a negative half-wave, and means for maintaining the positive terminals positive with respect to the negative terminals to a degree less than the voltage corresponding to the undesired voltage.

8. Apparatus for eliminating undesired peaks from signal voltages having, in combination, means for establishing a current in one direction along a predetermined path to render the path conducting, with the potential established by the current varying from positive to negative from one end of the path to the other end of the

path in the said direction, means for transmitting the signal currents along the path between the said ends in the opposite direction, means for maintaining the difference of potential between the said ends of the path at a value less than the voltage corresponding to the peaks to be eliminated from the signals, and means for maintaining the said value independent of the magnitude of the signals.

- 5 9. Apparatus for eliminating undesired peaks from signal voltages having, in combination, a rectifier, means whereby the rectifier rectifies the signal voltages to obtain a rectified signal voltage of predetermined polarity and suppresses the signal voltages of the opposite polarity, a second rectifier, means for establishing a current in one direction through the second rectifier to render the second rectifier conducting in the opposite direction, means for transmitting the signal currents through the second rectifier in the said opposite direction, means for stopping the current to render the second rectifier non-conducting in the said opposite direction when the voltages of the currents to be transmitted through the second rectifier attain values corresponding to the peaks to be eliminated from the signals, and means for preventing the direct current component of the rectified signals from becoming impressed upon the second rectifier.
- 10 10. Apparatus for transmitting along a path signal voltages not greater than a predetermined magnitude and suppressing signal voltages greater than the said magnitude, the said apparatus having, in combination, means for rectifying the signal voltages to obtain a rectified signal voltage of predetermined polarity, means for impressing upon the path a unidirectional voltage of substantially the said magnitude to establish in the path a unidirectional current for rendering the path conducting in one direction to the rectified voltages not greater than the said magnitude and non-conducting in the said direction to the rectified voltages greater than the said magnitude, means for transmitting the rectified voltages along the path in the said direction, and means for maintaining the value of the unidirectional voltage independent of the said magnitude.

- 35 11. Apparatus for transmitting voltages not greater than voltages of predetermined magnitude and suppressing voltages greater than the said magnitude having, in combination, two rectifiers each having an anode and a cathode, means for impressing upon the rectifiers voltages of substantially the said magnitude but of opposite polarity, means for transmitting the said voltages through one of the rectifiers in the direction from the anode to the cathode and through the other rectifier in the direction from the cathode to the anode, and means for rendering the anodes positive with respect to the cathodes upon the occurrence of a voltage of the said magnitude.
